(57) **CLAIM**

The ornamental design for a peeler blade, as shown and described.

DESCRIPTION

FIG. 1 is a top view of a first embodiment of a peeler blade showing my new design.

FIG. 2 is a bottom view thereof.

FIG. 3 is a left end view thereof.

FIG. 4 is a right end view thereof.

FIG. 5 is a front view thereof.

FIG. 6 is a back view thereof.

FIG. 7 is a perspective view of the peeler blade of FIG. 1.

FIG. 8 is a top view of a second embodiment of a peeler blade showing my new design.

FIG. 9 is a bottom view thereof.

FIG. 10 is a left end view thereof.

FIG. 11 is a right end view thereof.

FIG. 12 is a front view thereof.

FIG. 13 is a back view thereof.

FIG. 14 is an enlarged fragmentary view thereof; and,

FIG. 15 is a perspective view of the peeler blade of FIG. 8. The broken lines in the drawings are for illustrative purposes only and form no part of the claimed design.
